UNITED STATES PATENT OFFICE.

GEORGE F. SISBOWER, OF EAST ORANGE, NEW JERSEY, AND LOUIS E. PITTONI, OF NEW YORK, N. Y., ASSIGNORS TO NEW YORK COUCH BED COMPANY, OF NEW YORK, N. Y., A CORPORATION OF NEW YORK.

MATTRESS.

1,240,501.

Specification of Letters Patent. Patented Sept. 18, 1917.

Application filed January 23, 1915. Serial No. 3,930.

To all whom it may concern:

Be it known that we, GEORGE F. SISBOWER, a citizen of the United States, residing at East Orange, in the county of Essex and 5 State of New Jersey, and LOUIS E. PITTONI, a subject of the King of Italy, residing at New York city, county of New York, State of New York, have invented certain new and useful Improvements in Mattresses, the 10 following being a full, clear, and exact disclosure of the one form of our invention which we at present deem preferable.

For a detailed description of the present 15 form of our invention, reference may be had to the following specification and to the accompanying drawing forming a part thereof.

Our invention relates to mattresses of wire 20 fabric and involves means for protecting the stuffed mattress and the bed clothes from contact with the metal of the wire portion; also means for forming a side guard of non-metallic fabric.

Turning to the drawing, A represents a 25 wire mattress fabric of woven or link type which, as usual, is stretched taut on a metallic frame of which one of the end-bars is shown at B, the coiled springs D, D, etc., being interposed between the fabric A and 30 the bar B. At each end of bar B an upright angle-piece C is riveted and a cable E under tension is extended from each angle-piece C, parallel with the fabric A and about two inches above the edge thereof, to 35 a corresponding angle-piece (not shown) on the opposite end-bar. The side edges of the fabric A are also reinforced in the customary way with a similar cable F. To each cable E is attached one edge of a canvas or 40 other non-metallic strip H, the edge of the strip being folded over the cable and secured by a lacing cord running through eyelets h in the canvas. The lower edge of the 45 canvas strip is turned under the edge of the metallic fabric A and secured to that fabric, just inside of the reinforcing edge-cable F, by a lacing cord and eyelets. On the upper side of the metallic fabric A is placed a 50 sheet G of canvas or similar non-metallic material having eyelets along its edge by which it may be laced to the metallic fabric A, its side edges overlapping the inturned edges of the canvas strip H on the under side of metal fabric A. The same lacing

may be used, if desired, to secure both fabrics G and H to the metal fabric A, the former being above and the latter below the said metal fabric. It will be observed that both of the canvas fabrics G and H are readily detachable for washing, or for replacing with canvas of a different color or pattern to match the color or pattern of the stuffed mattress that is used. Besides protecting the stuffed mattress and bed clothes from contact with the metal of fabric A 55 and cable E, our arrangement of canvas strip H forms an improved type of side-guard that is washable, renewable and changeable to match the color or pattern of the stuffed mattress; while it also eliminates 60 contact of the hands, when making up the bed, with the rough surface such as is presented by the ordinary metallic-fabric side guards which scrape the hands by the projecting wire ridges and are liable to 65 certain broken wire strands that may cause 70 decided injury.

What we claim as new and desire to secure by Letters Patent is:

1. The combination with a metallic-fabric 80 mattress, of a side guard comprising uprights secured to the ends of said mattress, a cable connecting the upper ends of said uprights and located above the side edges of the mattress, and a flexible fabric guard 85 covering said cable and detachably connected therewith, said fabric having a lower edge overlapping said mattress, and means whereby said overlapping edge is detachably connected with the contiguous edges of 90 the mattress.

2. The combination with a metallic-fabric 95 mattress, of a side guard comprising uprights secured to the ends of said mattress, a cable connecting the upper ends of said uprights and located above the side edge of the mattress, and a flexible fabric guard having one edge overlapping and inclosing 100 said cable, lacings detachably connecting said overlapping edge with the body of said strip, the lower edge of said guard being extended beneath the contiguous edge of the members, and lacings detachably connecting said mattress and the extended lower edge 105 of said guard.

3. The combination with a metallic-fabric 110 mattress, of a side guard comprising uprights secured to the ends of said mattress,

a cable connecting the upper ends of said uprights and located above the side edges of the mattress, a flexible fabric guard covering said cable and having a lower edge 5 overlapping the contiguous edge of the mattress, a sheet of fabric covering the mattress and having its edge overlapping the lower edge of the guard, and means for detachably connecting the overlapping edges of 10 the guard and sheet to the mattress body.

4. The combination with a metallic-fabric mattress, of a side guard comprising uprights secured to the ends of said mattress, a cable connecting the upper ends of said 15 uprights and located above the side edges of the mattress, a flexible fabric guard cover-

ing said cable and having a lower edge overlapping the contiguous edge of the mattress, a sheet of fabric covering the mattress and having its edge overlapping the lower edge 20 of the guard, and lacings passed through the overlapping edges of the guard and sheet and also through the mattress body.

In witness whereof we have hereunto set our hands, before two subscribing witnesses, 25 this 20th day of January, 1915.

GEORGE F. SISBOWER.
LOUIS E. PITTONI.
